UNITED STATES PATENT OFFICE

2,425,149

PRINTING MACHINE

Walter T. Gollwitzer, Euclid, Ohio, assignor to
Addressograph-Multigraph Corporation, Cleve-
land, Ohio, a corporation of Delaware

Original application October 25, 1941, Serial No.
416,548. Divided and this application Decem-
ber 13, 1943, Serial No. 514,067

9 Claims. (Cl. 101—57)

1

This application is a division of my copending application Serial No. 416,548, filed October 25, 1941, which was, in turn, a continuation in part of my then copending application Serial No. 221,-841, filed July 28, 1938, now issued as Patent No. 2,296,277, patented September 22, 1942.

This invention relates generally to printing and like machines through which printing, printing and control or like devices are sequentially fed to have printing operations performed therefrom, and more particularly this invention relates to the platen mechanism of such machines whereby the desired printing impressions are made from the printing means of such devices or from other printing means so as to produce business instruments or the like.

In the use of printing machines of this character the printing impressions which are to be made usually pertain to identification data such as names, addresses and like information, and the printing impressions are made upon webs, sheets, business instruments and the like directly from the printing means of such printing, printing and control or like devices which are passed through the machine. The printing devices from which the printing impressions are made may take many different forms, but in most instances each printing device embodies a plurality of lines of printing characters, such as embossed type, from which printing impressions may be made upon a sheet, business form or the like. While a wide variety of printing devices may be employed in machines of the general character to which this invention pertains, the printing device disclosed in Mohler Patent No. 1,812,894, patented July 7, 1931, is typical of one form of printing device which may be employed. Another generally similar form of printing device adapted for use in connection with the platen mechanism of the present invention is disclosed in my Patent No. 2,132,412, patented October 11, 1938. A printing device of this character includes a rectangular carrier or frame having an embossable metal printing plate removably retained in position thereon, type characters being embossed on such a plate to appear in relief on the operative face thereof. Printing devices of a one-piece character may also be employed, such a printing device being shown in Duncan Patent No. 1,026,246, patented May 14, 1912, and in such one-piece printing devices the embossed type characters are formed in the single sheet of metal which forms the printing device. Insofar as some aspects of the present invention are concerned, the printing devices may be of the kind wherein type or printing characters are formed on suitable stencil paper, carried by a frame of cardboard or other material, and in such an instance the type characters are inked prior to the time when they are brought

2

into printing cooperation with a sheet or business form.

In a printing device of any of the various types hereinabove referred to, the body of the printing device may embody control means representing variable control data related to the identification data represented by the printing characters carried on each such device, and this control data may be utilized for various control purposes in producing the complete business instrument pertaining to each such device.

When the printing devices of the aforesaid character are passed through a printing machine or the like, the printing impressions are made directly from the type characters carried by the printing devices. These printing impressions usually pertain to identifications such as names, addresses, numbers, and the like, and such printing impressions are usually made through the use of impression or platen means which operate to effect printing cooperation of the sheet with the desired type characters of the printing devices or with supplemental type characters or printing means which may be mounted in the machine so as to cooperate with the printing devices to produce the desired business instruments or the like.

In the production of business instruments in the manner above outlined, the printing devices are passed through the printing machine in relatively large and continuous groups, and selecting mechanism in the machine is usually operable to determine whether or not business instruments are to be prepared with respect to the individual printing devices. Thus, in those instances where a business instrument is not to be prepared with respect to a particular printing device, the operation of the various mechanisms of the machine must be altered, and particularly, such operation of the platen must be varied so as to cause skipping of the particular printing device while at the same time assuring that proper impressions are made with respect to printing devices which may precede or follow the printing device which is thus skipped. In view of the foregoing, it is an important object of the present invention to enable platen mechanism to be constructed and arranged in a new and improved manner such that the selective operations of the various operative platen faces of such platen mechanism may be facilitated and readily controlled. A further and related object of the invention is to enable a single actuating means to operate plate mechanism embodying a plurality of operative platen faces, and to enable at least certain of such platen faces to be rendered effective or ineffective in a simple and expeditious manner.

Other and further objects of the present invention will be apparent from the following de-

scription and claims and are illustrated in the accompanying drawings which, by way of illustration, show preferred embodiments and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

In the drawings:

Fig. 1 is a plan view showing a printing machine embodying the features of the invention;

Fig. 2 is a fragmentary vertical sectional view taken substantially along the line 2—2 of Fig. 1;

Fig. 3 is an elevational view showing a typical business instrument or check produced in the machine;

Fig. 4 is an elevational view of a typical printing and control device from and under control of which operations are performed in the course of operation of the machine;

Fig. 4A is an illustration of the code under which data representing perforations may be produced in the printing and control devices;

Figs. 5, 6 and 7 are elevational views of proof sheets produced in the machine;

Fig. 8 is a rear view of the machine taken in section along the line 8—8 of Fig. 1.

Fig. 9 is an enlarged plan view taken from the line 9—9 of Fig. 2 and illustrating the proof printing platen mechanism;

Fig. 10 is a sectional view taken along the line 10—10 in Fig. 9;

Fig. 11 is an enlarged plan view taken from the line 11—11 of Fig. 2 and showing the main platen mechanism;

Fig. 12 is a sectional view taken along the line 12—12 in Fig. 11; and

Fig. 13 is a vertical sectional view taken substantially along the line 13—13 in Fig. 12.

The platen mechanism of the present invention is illustrated herein in an embodiment which has a wide variety of different uses, and for purposes of disclosure this form of the invention has been herein shown as embodied in a machine for producing complete business instruments, records and the like. Thus the platen mechanism of the present invention is illustrated as embodied in the machine which is fully illustrated and described in my copending application, Serial No. 416,749, filed October 27, 1941. Reference may, of course, be had to my said copending application for details of structure and operation, and the present disclosure is accordingly confined to those elements of the machine which are most directly related to the present platen mechanism. This machine, which is depicted in Figs. 1 and 2 of the drawings, is particularly adapted for the production of business instruments such, for example, as dividend checks S, Fig. 3, which include a main body Sm and a stub Sb joined together along a weakened portion SL to facilitate separation thereof.

As can best be ascertained by reference to Fig. 3, the check bears constantly reoccurring data C including, for example, the name and location of the company issuing the check, the words "Number" and "Shares" and kindred data as well as the border appearing on the check. The check also bears changing data A constituting an identification and characterizing the check and in the present instance this is an address comprising a name, street and number, and

city and state. Variable data V1 are also printed on the check and constitute, in this instance, the amount for which the check is to be payable, as well as variable data V2 which, in this instance, is the number of shares of stock owned by the person to whom the check is payable, both these data, in some instances hereinafter, being referred to as the variable data V. The check also bears other data such as the date E on which it was issued, a number N and a signature B.

The various data which appear on the check are, in the present instance, either printed on the check prior to the time it is introduced into the machine or such data may be printed on the check in the course of passage thereof through the machine, as will be explained more fully hereinafter. It is to be understood, however, that while in the present instance each check as S is cut to size and, for example, has the constantly reoccurring data C printed thereon prior to the time each such blank check, along with other similar blank checks, is introduced into the machine, each such blank check might be cut from a web and, for example, the reoccurring data C, as well as other data, might be printed thereon prior to the time the blank check is severed from the web and deposited on conveying means operative to carry the check through the machine to have other data printed thereon, and this could be done, for example, by resorting to an arrangement such as that described and claimed in United States Letters Patent No. 2,041,183, patented May 19, 1936.

In the present instance the address or changing data A are printed on the check directly from type characters as T, Fig. 4, on a printing and control device as D and the variable data V are printed under control of such a printing and control or like device. It is preferred to employ a printing and control device as D in the present machine for so to do eliminates the necessity of checking printing devices or the like bearing, for example, type characters as T against separate record cards or the like, under control of which the variable data as V could be printed, for the printing and control devices as D, including both type characters as T and means under control of which variable data as V may be printed, insure that, in the course of operation of the present machine, the changing data as A printed from type characters T and the variable data as V will be printed on a particular check as S so as to thereby insure that related data A and V appear on a single check, it being understood that the type characters T and the means under control of which the variable data V are printed and which are related one to the other are embodied in a single printing and control device as D.

It is to be understood, however, that while reference is made herein to printing and control devices and that while such a device is illustrated and particularly described herein, there are many devices which are applicable for use in the present machine or for use with the platen mechanism of this invention for it will be clear that the present machine might be arranged to utilize devices which constitute either only a printing means or only a control means and that therefore, in so far as certain mechanisms in the present machine are concerned, for example, the platen means operative to produce printed impressions from the printing and control devices D, the term printing and control device is used herein in a generic rather than in a limiting and strictly definitive sense.

The printing and control devices D used in the present machine are stored in a drawer or the like of conventional form when not in use and when these devices are to be passed through the machine, they are introduced into the magazine H, Figs. 1 and 2, provided at the rear of the machine. Means are provided for withdrawing the printing devices D one by one from the magazine H and these means are operative to advance these devices through the machine in a step-by-step manner so that the printing and control devices successively come to rest in positions or stations whereat printing, sensing or other operations may be performed thereon or under control thereof, and after the devices have been advanced through such stations in the machine they pass through a discharge chute adapted to receive these devices.

The present machine is equipped with an arrangement whereby the printing and control devices, after passage thereof into the aforesaid discharge chute, are returned to the drawer or the like from which they were removed when they were introduced into the magazine H. To this end suitable means are provided in the machine for the reception of two drawers as shown in my copending application Serial No. 416,749, filed October 27, 1941. Arrangements, for example, to which resort may be had for so supporting drawers in the machine, and for insuring the return of the printing and control devices to the drawer or the like from which they were removed when introduced into the magazine H, are those which are disclosed in my copending application, Serial No. 403,272, filed July 21, 1941.

Printing and control device

A typical printing and control device which may be utilized in the present machine is illustrated in Fig. 4 and is of the character constituting the subject matter of United States Letters Patent No. 2,132,412, patented October 11, 1938. It is to be understood, however, that this device is typical of other devices which may be utilized in the machine for while the aforesaid printing and control device embodies a metal plate on which the aforesaid type characters T are embossed and includes a card which overlies a portion of the carrier or frame of the printing and control device, so that data representations may be afforded by perforations in such card and frame, resort could be had to a cardboard or other carrier in which data representing perforations, embossures or the like might be formed, and such a frame might embody, for example, a stencil paper in which type characters from which impressions might be made might be cut.

The typical present printing and control device illustrated in Fig. 4 includes a frame 75 having, in this instance, a metallic plate 76 removably retained thereon by fixed retaining devices 77, a bed 78 at the lower end edge of the frame 75 and yieldable or compressible retaining tongues 79. When one or the other of the tongues 79 is depressed, the plate 76 may be slid endwise from the retaining devices 77 and the bed 78 to thereby enable one such plate as 76 to be replaced by another such plate when the need so to do arises as, for example, upon a change in the post office address of the person or the like whose name may be printed from type characters as T included on the plate 76. In the present instance the type characters T are embossed on the metallic plate 76 to appear in relief on one face thereof and in intaglio on the opposite face,

impressions being made from the relief faces of the type characters T when the printing and control device D is fed into printing relation with the platens included in the machine that are described hereinafter.

The printing and control device D shown in Fig. 4 also bears a card 80 on which an impression is made from at least selected of the type characters T so that the data which may be printed from the type characters T may be readily ascertained whereby handling of the device D for filing and like purposes is facilitated. The card 80 is removably retained on the frame 75 above the plate 76 by suitable retaining devices 81 and the bead 82 along the top edge of the frame.

In the present instance the card 80 is of a length substantially equal to the length of the printing plate 76 and therefore extends over an area of the frame whereat coded data representing perforations may be formed, and to this end the printing and control device D, as viewed in Fig. 4, has the impression 83, made from at least selected of the type characters T on this card confined to the left-hand portion of this card so that the right-hand end of this card affords an area whereat the coded data representing perforations 85 may be formed, and for the purposes of this description the aforesaid card 80 will hereinafter be referred to as a control card.

While the coded perforations 85, or other data representations, as embossures or the like, may be produced on the frame 75 or the card 80 and this frame in accordance with any desired code so as to be representative of numerical or other data, I prefer to produce these perforations in accordance with the code illustrated in Fig. 4A for so to do enables me to utilize a multiplying mechanism in the machine, such as is described hereinafter and in full detail in my United States Letters Patent Nos. 2,296,276 and 2,296,277, patented September 22, 1942.

Sheet feeding and form printing

In the present instance impressions are made from type characters as T on the printing and control device as D onto the check as S by a main platen MP, and similar impressions are made onto the web W by what will be referred to hereinafter as the proof printing platen PP. As can best be ascertained by reference to Fig. 1, the platens MP and PP are aligned one with the other along the guideway G, Fig. 2, through which the printing and control devices are advanced from the magazine H to the discharge chute 231, Fig. 8, from which they are discharged one by one into the appropriate collecting drawer.

As explained hereinabove, the checks or sheets as S, in the present instance, are cut to size and have certain data printed thereon prior to the time they are introduced into the machine to be fed therethrough and in the illustrated machine the sheets are mounted on the sheet-supporting platform 86, Fig. 1, of the sheet feeder SR which operates to withdraw the most inwardly disposed of such sheets from the stack thereof disposed on the platform 86 and thereafter to pass such sheet into the machine. While resort may be had to various types of sheet-withdrawing means, that disclosed in my copending United States application Serial No. 416,636, filed October 27, 1941, is typical of the means to which resort may be had for the purpose of withdrawing the sheets or checks one at a time from the supply thereof

introduced into the machine as by being disposed on the platform 86.

Moreover, resort may be had to an arrangement such as that shown and described in United States Letters Patent No. 2,288,350, patented June 30, 1942, and in such circumstances the sheet receiver SR is supplanted by a web supporting, feeding and severing means such as described in my last referred to United States Letters Patent which functions to sever sheets from the web and to deposit the sheets on the sheet conveying means, generally indicated by 87, Fig. 1, which may be, for example, of the character shown and described in United States Letters Patent No. 2,211,772, patented August 20, 1940, the sheet advancing means 87 being operative to feed the sheets or checks S along a sheet guideway SG which is afforded across the table top TT of the machine.

The sheet conveying means 87 is not only operative to advance the sheets or checks as S through the machine but also functions to bring the sheets to rest in the sheet guideway SG in operative association with the platen MP and a printing and control device disposed in printing relation therewith to thereby have impressions made on the sheets as S at selected positions thereon, the variable data as V also being printed on the checks as S when they are disposed in operative relation with the platen MP as aforesaid.

After, for example, changeable data as A and variable data as V have been printed on the checks as S during the time they are disposed in operative association with the platens MP and MP-2, the sheet conveying means 87 functions to advance the sheets to the printing couple PC, Fig. 1, which may be, for example, of the character disclosed in Letters Patent No. 1,955,814, patented April 24, 1934, or in Letters Patent No. 2,165,535, patented July 11, 1939. However, in the illustrated machine, I employ a well-known printing unit embodying a printing roller and a platen roller and so arranged that either separate type or an electroplate may be mounted on the printing roller, and reference may be had to, for example, Letters Patent Nos. 816,311, 970,411, 990,207, 1,031,311, 1,094,065, 1,148,940 and 1,647,560 for a full disclosure of a printing couple or unit suitable for the purposes of the present invention.

Upon passage of the sheets from the printing couple PC, the sheets are discharged to a suitable sheet collector as SC to be stacked one upon the other in the usual manner shown, for example, in Fig. 1.

When the printing and control devices advance into operative association with the platen PP, impressions are made therefrom, as stated above, on the web W which is advanced into printing relation with the printing platen PP and a printing and control device disposed in printing relation therewith to have impressions made therefrom, for example, of changeable data A and variable data V, and after passage of those portions of the web W which receive such impressions, the web W is divided into pages. Hence, the means operative to feed the web W to and from operative relation with the platen PP constitute what is known as a pager and proofer mechanism. In the present instance I have shown a pager and proofer mechanism PM, Fig. 1, generally of the character shown and described in my copending application Serial No. 320,778,

filed February 26, 1940, but it is to be understood that resort might be had to other equivalent arrangements for feeding the web into printing relationship with the platen PP and for thereafter dividing the web into what are called proof pages.

5 In the operation of the machine the printing or printing and control devices D are in this instance fed one by one from the magazine H along a printing device guideway G so as to come to 10 rest successively at a plurality of different positions or stations of which two stations constitute printing positions. The printing device guideway G is formed by means including spaced supporting and guiding rails 1701 and 1702 which 15 extend in the present instance from front to rear of the machine and are carried by a machine frame designated generally as 1703. In such advancing movement along the guideway G each printing device comes to rest successively at a 20 sensing station II, Fig. 2, a first printing station III, an intermediate station IV and a second printing station V, after which the printing device is discharged downwardly into the chute 231 of the collecting means.

25 At the first printing station III the printing device may be utilized in producing a business instrument such as the check S, the sheets S being advanced along the guideway SG into printing position III beneath the platen MP. When a 30 sheet S is thus positioned, it is located directly over an inked ribbon IRb, Fig. 2, and the printing device D is located beneath the inked ribbon and on top of an anvil 1705 which is supported between the two rails 1701 and 1702. Through 35 actuation of the platen MP, in a manner to be hereinafter described, a printing impression may be made from the printing device onto the sheet S so as to provide the identification data A thereon. Other means are provided in the machine 40 for printing the variable data V, the number N, the signature B and the form F, and since the particular means employed in printing the signature and the form do not constitute a part of the present invention a detailed description 45 thereof will not be incorporated herein. It will be observed, however, in Figs. 1, 11 and 12 of the drawings, that a platen mechanism MP-2 is provided adjacent to the platen mechanism MP, and this platen mechanism MP and MP-2 is utilized 50 in printing the variable data V and the number N on the sheet S, as will be hereinafter described. The variable data V is, in the present instance, printed under the control of a multiplying mechanism, as M, which, as described in my copending application, Serial No. 416,635, filed October 27, 1941, controls the setting of type segments 55 1706 of the variable printer VP disposed beneath the platen MP-2, and the multiplying mechanism as M is controlled by the coded perforations 60 85 in the control card 80 of a printing and control device D sensed at sensing station II.

65 After a printing device D has come to rest station III and a printing operation has been made therefrom, it is advanced through the idle station IV and thence to the second printing station V, and at this station a proof sheet is prepared. As hereinbefore pointed out, the proof sheet is prepared through printing upon a web such as the web W which is withdrawn from a 70 roll R supported in front of the machine on a projecting shaft WS. This web W is led across the printing station V and about stationarily mounted guide rollers 1707 and 1708 to thereby 75 guide the lower run of the web under the platen mechanism PP and thence upwardly and then

forwardly over the platen mechanism PP in spaced relation thereto. The web W is extended forwardly from the guide roller 1708 into the pager and proofer mechanism PM, which mechanism incorporates a web feeding means for withdrawing the web from the roll R. The pager and proofer mechanism PM also includes means for dividing the web into sheets of a predetermined size, and these sheets are discharged into a receiving tray 916. The web W is moved beneath the platen mechanism PP with a step-by-step motion so that the platen mechanism PP may cooperate with an anvil 1715 to produce printing impressions on the web W. The anvil 1715 is located between the two rails 1701 and 1702 so as to be supported at least in part by the two rails.

The proof sheets which are thus formed by the pager and proofer mechanism PM may have different characteristics such, for example, as those characteristics embodied in the proof sheets PS1, PS2 and PS3 which are illustrated in Figs. 5, 6 and 7, respectively, of the drawings. The proof sheet PS1 constitutes the normal proof sheet, and the total of the numerical items VI printed thereon are accumulated by means included in the machine, and this constitutes a page total PTT which is printed at the bottom of the sheet. In many uses of the machine it is desirable to obtain other totals which may include the page totals from a number of sheets, such as the sheet PS1, and such a total is often termed a ledger total which is indicated on the proof sheet PS2 as the ledger total LT. It will be observed that on the proof sheet PS2, a page total PTT is printed prior to the printing of the ledger total LT. In a run of the machine there may be a large number of ledger totals LT and at the end of the run it is customary to print the total of all of the items printed in the course of the run of the machine. This is termed grand total and is indicated by the grand total GT printed on the proof sheet PS3. When a grand total GT is printed the present machine also prints the page total PTT and the ledger total LT prior to the printing of the grand total.

The two platens MP and PP are arranged for independent actuation through hydraulic actuating means, and to this end the anvils 1705 and 1715 embody hydraulically actuated piston and cylinder devices which are operated through the medium of individually operable pumps 1720A and 1720B. The pumps 1720A and 1720B are similar in form and construction and are capable of independent actuation from a common power source as will hereinafter be described.

The number of type characters that may appear on various printing and control devices may vary widely from device to device, and in order to prevent a heavy impression being made when only a few type characters appear on a printing and control device and a light impression being made when a large number of type characters appear, the present invention has provided a platen arrangement which will make uniform impressions even under conditions entailing extreme variations in the number of type characters.

One factor which contributes to the production of uneven impressions is spring, that is, twisting, in the means or member supporting the impression-making member, on which, in the present instance, is the platen MP. This may be overcome, to a substantial extent by employing relatively rigid members to support the im-

pression-making member such as the platen MP and in the present instance a pair of relatively heavy and substantial side members 538 and 539, Figs. 2, 8 and 11, are provided. The members 5 are substantially U-shaped and are formed from relatively thick material. The U-shaped configuration of the side member 538 is afforded by substantially parallel arms 543 and 544, and an interconnecting arm 545, similar parallel arms 10 and a similar interconnecting arm constituting the side member 539.

The arms 543 are secured together by a tie rod 546, Fig. 2, a spacing sleeve 547 being disposed about this tie rod between these arms. The arms 15 544 are secured together by a tie rod 548 and a surrounding spacing sleeve 549 disposed about this tie rod intermediate these arms. A bar 550 extends between the arms 541 and 544 near the front ends thereof and the ends of this bar are rigidly connected to these arms. The foregoing arrangement of side members, tie rods, spacing sleeves and bar affords a rigid unitary structure which comprises the movable portion of the impression making means of which the platen P is a part.

As is well understood in the art to which printing machines of the kind to which this invention pertains find their principal use, it is essential that the face of an impression member such as the platen P be in strict parallelism with the face of a printing and control device bearing type characters from which an impression is to be made, this preventing smearing and kindred objectionable conditions in impression operations. This is best attained by providing the point of pivotation of the movable part of the impression means in the plane in which the faces of the type characters from which impressions are to be made will lie and in the present machine this is accomplished by securing blocks 552 to the upper edges of the side plates 1701 and 1702 which form part of the guideway G and are shown in Figs. 7 and 12. V-shaped notches are provided in the blocks 552 and the apices of these V-shaped notches lie in the aforesaid plane in which the type characters will lie when a printing and control device is disposed on the anvil 1705. Downward movement of the platen MP is limited by a cross bar 1725 bolted on the downwardly flanged edge 1726 of the anvil 1705, the ends of the cross bar 1725 being arranged to act as abutments in the path of the arms 544 of the U-shaped frame members 538 and 539.

Blocks 556 are secured to the arms 545 of the side members 538 and 539 and these blocks are formed to provide knife edges which are seated in the V-shaped notches of the blocks 552 so that these knife edges rest in the respective apices afforded by these V-shaped notches. Such mounting of the movable portion of the impression means enables this movable portion to be moved with minimum friction, and this arrangement insures that minimum wear will occur in the course of long use of the impression means. Furthermore, the seating of the knife edges in the apices of the notches assures that the point of pivotation of the movable part of the impression means will lie in the plane above described.

While the rigid construction above described and the assurance that the face of the impression member will lie in the proper plane contribute to the production of the desired uniform impressions, this can be further assured by causing the impression pressure to be effected by a squeezing action which may be the result of the

application of retroactive forces and in order to accomplish this I resort to an hydraulic system for applying the impression pressure.

The actuating or impression forming movement of the platen MP is obtained through the medium of a piston 560 mounted in a vertically extending cylinder 559 formed in the anvil 1705, and when hydraulic liquid under pressure is introduced through passage 1727 into the upper end of the cylinder 559 the piston 560 is forced downwardly in the cylinder 559 so as to bear against an adjustable abutment 1728 provided in a cross bar 550 which extends between the two lower arms of the platen supporting frame. It will be observed that the hydraulic liquid under pressure is supplied through a pipe 1730, and the passage 1727 is continuous from the pipe 1730 to the upper end of the cylinder 559. When the pressure of the hydraulic liquid in the cylinder 559 is released, the platen MP is returned to its elevated position by one or more springs 605 connected between the cross member 545' and the machine frame 1703.

The platen mechanism PP is best shown in Figs. 1, 2, 9 and 10 wherein it will be observed that the platen mechanism PP embodies a U-shaped supporting and actuating frame 1735 which is in a broad sense similar to the U-shaped frame provided for the platen mechanism MP. The frame 1735, however, has but a single U-shaped member which has an upper arm 1736, a cross member 1737 and a lower arm 1738. As shown in Figs. 9 and 10, the connecting or cross member 1737 has oppositely projecting mounting arms 1739 and 1740 at the ends of which aligned knife edge bearing members 1741 and 1742 are mounted. The knife edge bearing members 1741 and 1742 are arranged to rest in V-shaped bearing notches such as the slot 1743 shown in Fig. 9. The bearing notches 1743 are formed in the side members 1744 of a relatively rigid supporting frame which is secured by bolts 1745 to the rail 1702.

The frame 1735 is urged in a clockwise direction toward an inactive or platen-retracting position by means of a pair of springs 1746, the lower ends of the springs 1746 being connected to an anchoring rod 1747 while the upper ends thereof are connected to anchoring pins 1748 which are mounted in the connecting portion 1737 of the frame 1735 so as to project therefrom in a direction opposite from the arms 1736 and 1738 thereof.

The platen supporting frame 1735 is actuated by hydraulic means which includes a vertically extending cylinder 1750 formed in the anvil 1715, and a piston 1751 which is reciprocal in the cylinder 1750. The lower end of the cylinder 1750 is open so that a bearing head 1752 on the lower end of the piston may bear against an adjustable stop member in the form of a screw 1753 mounted in the lower arm 1738. When hydraulic liquid under pressure is supplied to the upper end of the cylinder 1750 through a passage 1744, Fig. 10, the piston 1751 is forced downwardly until an abutment surface 1756 on the arm 1738 engages an abutment surface 1757 formed on a stationary plate 1758, and such limitation of movement of the platen supporting frame 1735 insures that the platen PP will in every instance produce uniform printing impressions regardless of the variations in the number of printing characters embodied in the printing devices D.

When the pressure of the hydraulic liquid is reduced at the end of a printing operation, the

springs 1746 act to return the platens to their retracted or upper positions, and such retracting movement is in the present instance limited by stop means which is mounted on the upper end of the piston 1751. Thus, as shown in Fig. 10 of the drawings, this stop means comprises a washer 1760 mounted beneath the head of a mounting screw 1761, the mounting screw extending through a spacing sleeve 1763 and being threaded into the upper end of the piston 1751. The upper end of the cylinder 1750 is suitably recessed as the sleeve 1763 to provide clearance for the head of the screw 1761, and hence when the piston 1751 is forced upwardly the head of the screw enters the recess 1763 until the washer 1760 is seated against the upper wall of the cylinder. In the present instance this structure is also utilized in securing a cup washer 1765 in position on the top of the piston 1751, and this end is attained through the use of a clamping plate 1766 which is positioned within the cup washer 1765 and beneath the lower end of the spacing sleeve 1762. Thus when the screw 1761 is tightened, the clamping plate 1766 is urged downwardly into the clamping relation with respect to the cup washer 1765. With the stop means thus provided the piston 1751 is invariably located so that the upper edge of the cup washer 1765 is located beneath the inlet opening of the cylinder 1750 to thereby provide for unrestricted and unobstructed entry of hydraulic liquid into the cylinder. In the present instance this inlet includes the vertical bore 1755 which intersects with a horizontal bore 1768, Fig. 2, and the bore 1768 is so located that it provides the clearance or recess 1763 for the head of the screw 1761. The bore 1768 is permanently closed at one end by a plug 1769, while an upwardly extending bleed opening is provided at the other end, this bleed opening being closed by a removable screw-threaded plug 1770 which may be removed for the purpose of bleeding air from the hydraulic system. Similar stop structure and a similar bleed opening are also provided in connection with the piston and cylinder means of the platen MP.

The platen mechanism PP is utilized in the production of proof sheets of the general character shown in Figs. 5, 6 and 7 of the drawings, and the arrangement of the proof sheet in this instance is such that the variable data VI are printed in the middle column of the proof sheet while the number N is printed in the third or right-hand column of the sheet. Thus as shown in Fig. 10 of the drawings, the variable printer VP is disposed just to the left of the anvil 1715, and the multiplying mechanism M, while a numbering mechanism 1781 is disposed just to the left of the variable printer.

Separate or individual platen sections are provided on the platen supporting frame 1735 for the formation of the identifying impressions A, the variable data impressions V, and the numbering impressions N. Thus a platen section 1785 is disposed upon the arm 1736 for cooperation with a printing device located at printing position V over the anvil 1715; a platen section 1786 is mounted on the arm 1736 for cooperation with the variable printer VP; while a platen section 1787 is disposed on the arm 1736 for cooperation with the numbering mechanism 1781. A single inked ribbon IRb-2 cooperates with all of the platen sections thus provided, and in the present instance this inked ribbon extends beneath and longitudinally of the arm 1736 so as to be posi-

tioned beneath all three platen sections. At its right-hand end, as viewed in Fig. 10, the ribbon IRb-2 passes through a clearance slot 1739' formed in the mounting arms 1739 and 1741.

For the purpose of supporting the platen section 1786 a mounting plate 1788 is secured on the bottom of the arm 1736 adjacent the end thereof by means such as screws 1789. The mounting plate 1788 has a forwardly projecting and downwardly offset portion 1790 beneath which the platen section 1786 is mounted. Such mounting is in the present instance obtained by means of a pair of spaced leveling screws 1791 which extend downwardly through threaded openings in the plate 1788 so that the reduced lower ends rotatably engage suitable sockets formed in the upper face of platen section 1786. A headed screw 1792 extends downwardly through the mounting plate 1790 and is threaded into the platen section 1786 substantially midway between the two leveling screws, and by suitable adjustment of the screws 1791 and 1792 the platen section 1786 may be adjusted so that its lower or operative face will be located in the proper relation to the variable printer VP when the platen supporting frame 1735 has been actuated to its active position. The platen section 1786 serves merely as a backing member for the hammer-actuated type elements of the variable printer VP, and hence a printing impression will not be made by the platen section 1786 as a result of the lowering of the platen unless the type elements of the variable printer are actuated by their hammer mechanism.

The platen section 1785 which is utilized for printing the identification data A is arranged so that it may be shifted selectively between active and inactive positions; and provision is also made for leveling the lower or operative face of the platen section 1785 so as to assure proper cooperation thereof with the type characters of the printing devices. In accomplishing this result the platen section 1785 is supported beneath a platen mounting plate 1795 which is in turn supported beneath the arm 1736. The platen supporting plate 1795 is urged in an upward direction by means of a spring 1796 which is located in a recess 1797 in surrounding relation to a headed bolt 1798, and this bolt extends downwardly through the arm 1736 and the plate 1788 and is threaded into the mounting plate 1795. Thus the mounting plate 1795 is constantly urged in an upward direction and into contact with a plurality of laterally spaced leveling screws 1799 which extend downwardly through the projecting edge portions of the plate 1788 so as to bear upon the upper face of the mounting plate 1795. The mounting plate 1795 may therefore be leveled through appropriate manipulation of the screws 1799, and the adjusted relation is maintained by retaining springs 1800 which bear against the sides of the heads of the leveling screws 1799.

The platen section 1785 is supported beneath the mounting plate 1795 upon a plurality of headed screws 1801 which are located in sockets formed in the mounting block 1795, and the screws 1801 project downwardly through the bottoms of the sockets and are threaded into the top of the platen section 1785. Expansive coil springs 1802 surround the screws 1801 within their mounting sockets, and the springs 1802 serve to urge the platen section 1785 upwardly toward an inactive position such that a printing impression will not be made by the platen section 1785 even though the platen supporting frame 1735 is shifted

to its active position. The platen section 1785 may be shifted downwardly against the force of the springs 1802 by means of a pair of cam shafts 1805 which are mounted transversely in the mounting plate 1785 so that the lowermost surface of the cam shafts may be rotated into different engaging relationships with respect to certain portions of the platen section 1785. The cam shafts 1805 have flat portions 1806 formed thereon in such a position that when the two flat portions are located in opposed relation to the platen section 1785, this platen section assumes its retracted position. When the two cam shafts 1805 are rocked in a counterclockwise direction from such a relationship, and to the relationship shown in Fig. 10, the flat sections 1806 are moved out of position, and the cam shafts are effective to move the platen section 1785 downwardly against the force of the springs 1802. This moves the platen section 1785 to its active position of Fig. 10 so that the platen section 1785 is conditioned to produce a printing impression in the event that the platen supporting frame 1735 is moved to its active position. The two cam shafts 1805 are moved in unison through the medium of arms 1807 which are fixed thereto and are connected by a link 1808.

When the arm 1736 is moved upwardly a roller 1809 mounted on an arm 1810 fixed to the left-hand cam shaft 1805 engages an abutment surface 1811 formed on the lower edge of a stationary plate 1812, the plate 1812 being mounted on a stationary cross member 1813 of a frame 1814 which supports the guide rollers 1707 and 1708.

Thus in the upward movement of the arm 1736 the stationary abutment 1811 acts on the roller 1809 to shift the cam shafts 1805 to the positions shown in Fig. 10, and as a result the platen section 1785 is invariably located in its active position

40 when the platen supporting arms 1736 is in its elevated position. Hence when the cam shafts 1805 are allowed to remain in this relationship during the next downward stroke of the arm 1736, the platen section 1785 will be effective to produce a printing impression from the printing device located at printing position V. Provision is made, however, for rocking the cam shafts 1805 in a clockwise direction during the course of a downward movement of the arm 1736, thereby to cause the platen section 1785 to assume its inactive position before the platen supporting arm 1736 reached the end of its downward stroke. In the present instance this means comprises a swingably mounted arm 1815 suspended from the cross member 1813 in such a manner that the laterally projecting lower end 1816 thereof may be shifted to a position beneath the roller 1809, thereby to prevent downward movement of the roller 1809 in the course of a rocking movement

55 of a platen supporting arm 1736. The arm 1815 is urged toward an inactive position by means of a spring 1817 which acts between the arm 1815 and a supporting or anchoring rod 1818, and means are provided to shift the arm 1815 to an active position when it is desired to render the platen section 1785 inactive. This means in the present instance comprises a solenoid 1820 having its armature connected by means of a rod 1821 to the arm 1815, and whenever the platen section 1785 is to be rendered inactive the solenoid 1820 is energized. This shifts the arm 1815 to its active position to thereby cause the roller 1819 to be held against downward movement with the result that rocking movement is imparted to the cam shafts 1805 to bring the flat sections 1806

thereof into alignment with the opposed upper face portions of the platen section 1785. The platen section 1785 therefore is retracted to its inactive position and a printing impression is not made from the printing device located at printing position V. In the upward or retracting movement of the platen supporting arm 1736 the abutment 1811 acts upon the roller 1809 to rock the shafts 1805 to the position shown in Fig. 10 and the platen section 1785 is thereby conditioned to produce a printing impression in the next cycle of operation of platen supporting arm 1736.

The platen section 1787 which is used in printing the numbers N upon the proof sheet is also mounted for relative shifting to thereby avoid printing of a number in certain cycles of operation of the platen supporting frame 1735. As herein shown an arm 1825 is pivoted at 1826 on the plate 1790 and the arm extends to the left in Figs. 9 and 10 to a point beyond the left-hand end of the platen section 1786. The platen section 1787 is supported beneath the left-hand end of the arm 1825 so as to project downwardly through a slot 1827 formed in the supporting plate 1790. The plate section 1787 is supported by means of a screw 1828 which extends through the arm 1825 and is threaded into the platen section 1787. By tightening the screw 1828 the platen section 1787 may be drawn into engagement with a pair of spaced leveling screws 1829 which are associated with the platen section 1787 in a manner substantially similar to the association employed with the leveling screws 1791.

When the platen supporting frame 1735 is rocked in an impression-making direction, the arm 1825 of the platen section 1787 is yieldingly restrained against downward movement by means of a spring 1830 which surrounds a link 1831 pivoted at its lower end to the arm 1825. The link 1831 extends upwardly and slidably through an opening in a block 1832 which is mounted on the end of the anchoring rod 1818, and the spring 1830 rests at its lower end on the block 1832. At its upper end the spring acts against a pair of nuts 1833 threaded onto the link 1831. Thus the platen section 1787 tends to remain in an upper or inactive position when the platen supporting arm 1736 is lowered through an impression-forming stroke, and means is provided for operatively connecting the platen section 1787 to the arm 1736 when an impression is to be made by the platen 1787. In the platen structure herein illustrated this end is attained through the provision of abutment means carried on the arm 1736 and adapted to be shifted into a position over the arm 1825, thereby to lock the arm 1825 in a predetermined relationship to the arm 1736, and hence the yielding action of the spring 1830 is ineffective to retain the platen section 1787 in its inactive position. In the present instance the abutment means comprises a slide rod 1835 extending slidably through upstanding mounting flanges 1836 and 1837 carried on the plate 1790. The slide rod 1835 has an abutment disc 1838 fixed thereon in such a relationship that it may be shifted from the position shown in Fig. 9 to a position wherein it overlies the arm 1825. Such shifting movement may be imparted to the slide rod 1835 by means of a solenoid 1840 which has its armature 1841 operatively connected to one end of the slide rod 1835. A spring 1842 surrounds the armature 1841 and acts on the armature to normally shift the slide rod 1835 and the disc 1838 to their inactive positions of Fig. 9.

It will be evident that the platen mechanism

PP provides for selective performance of printing operations by the platen sections 1785 and 1787, and since the platen section 1786 is associated with a hammer type of variable printer, the three classes of data embodied in a proof sheet may be selectively printed with the present mechanism.

As hereinbefore pointed out the hydraulic cylinders of the two platen mechanisms MP and PP are independently supplied with hydraulic liquid through independently and selectively operable pumps 1720A and 1720B, which, as shown in Fig. 8, are similar in form and construction and are both operated from a drive shaft 1850. The drive shaft 1850 is driven from a motor 1851 through a belted connection shaft 1853 to a drive pulley 1854 fixed on the shaft 1850. The pumps 1720A and 1720B are adapted for individual actuation through means which include one-revolution clutches as disclosed in detail in my aforesaid pending application Serial No. 416,548 filed October 27, 1941, and the clutches which control the pumps 1720A and 1720B are governed respectively by solenoids 1910A and 1910B. It will be evident that through selective energization of the solenoids 1910 the two pumps 1720A and 1720B may be selectively operated through the platen actuating cycles.

The platen MP—2, as hereinbefore pointed out, is utilized to cooperate with the variable printer VP to print the variable data V on the sheet S, and this platen is also utilized to print the number N on the sheet S through the medium of a numbering mechanism 1965 disposed beneath the platen MP—2 beside the type segments 1706 of the variable printer VP. The platen mechanism MP—2 as herein shown comprises a pair of L-shaped side frames 1966 held in spaced relation by a spacing bar 1967 at one end and by a cross bar 1968 at the other end. At said one end the frame members 1966 have downwardly extending knife edge bearing members 1969 which rest in V-shaped bearing notches 1970 provided on the frame of the variable printer VP. A pivotally mounting latching bar 1971 is engaged with the spacing bar 1967 to hold the platen MP—2 in position on its knife edge bearings.

The cross bar 1968 is utilized as a mounting for a pair of platen sections 1973 and 1974, these two platen sections being utilized to print the number N and the variable data V, respectively. The location of these platen faces on the cross bar 1968 is governed primarily by the desired location of the impressions which are to be formed thereby on the sheet S, and in the present instance the platen section 1973 is disposed to the left and somewhat rearwardly of the platen section 1974, as viewed in Fig. 11, since it is desired to produce correspondingly located impressions N and V on the sheet S. Each of the platen sections 1973 and 1974 is mounted by means of leveling screws 1975 and a securing screw 1976, the securing screw being utilized to hold the platen sections upwardly against the leveling screws 1975. This arrangement is similar to the leveling arrangement employed in mounting the platen sections 1786 and 1787, hereinbefore described.

In accordance with the present invention the platen MP—2 is actuated through its printing stroke by the same platen actuating means that is used to actuate the platen MP, and this end is attained by operatively interconnecting the two platens MP and MP—2 when a printing impression is to be made by the platen MP—2. For

this reason the knife edge bearings as 1969 of the platen MP-2 are disposed in substantial alignment with the knife edge bearings of the platen MP, thereby to cause the platen sections 1973 and 1974 to move along a path which is similar to the path of the platen face on section 625 of the platen MP. It will be understood that when the platen MP is actuated through its printing stroke to print the changeable data A on the sheet S there is a printing device D located on the anvil 1705. The printing device advancing means is then operated to advance the printing device D from station III, that is, from its position over the anvil 1705, and prior to the time when another printing device is fed into printing position III, the platen MP may be actuated without producing either a printing impression or an offset. It is during such periods when a printing device D is not located at station III that the numbering and variable data impressions are made upon the sheet S, and the desired interconnection between the platen MP and the platen MP-2 is in the present instance effected by a latch mechanism.

The details of construction and operation of this latch mechanism are illustrated in Figs. 11 and 12 of the drawings, wherein it will be observed that a relatively rigid mounting rod 1978 is secured on the left-hand frame member of the platen MP so as to extend to the left, as viewed in Fig. 11. At its end the mounting rod 1978 carries a pivotally supported latch 1980 having a downwardly facing shoulder 1981, Fig. 12, adapted to engage the upper forward edge of the cross bar 1968. In the event of such engagement of the shoulder 1981 with the cross bar 1968, it will be evident that operation of the platen MP through its printing stroke will produce corresponding operation of the platen MP-2 through its printing stroke.

The latch 1980 is normally urged toward such a latching relationship with respect to the platen MP-2 by actuating rod 1983 pivoted at its forward end to the latch 1980 at 1984. The rod 1983 extends rearwardly and slidably through a cross bar 1985 which extends between the side frame members 1966. A spring 1986 surrounds the rear portion of the rod 1983 so as to act between the cross bar 1985 and an abutment 1987 on the rear end of the rod 1983.

The platen MP-2 is normally held in an elevated or inactive relationship by a spring 1988 connected at its upper end to an anchor 1989 on the platen MP and connected at its lower end to an anchor 1990 on the adjacent frame 1966 of platen MP-2. The spring 1988 normally holds the platen MP-2 in such an elevated position that the rear face 1991 of the latch 1980 engages the forward face of the cross bar 1968 of the platen MP-2. Thus the shoulder 1981 is normally disposed somewhat below the upper face of the cross bar 1968, and when the latch 1980 is to be operatively engaged with the platen MP-2, the platen MP-2 is actuated slightly in a downward direction to thereby locate the cross bar 1968 somewhat below the level of the shoulder 1981, and while this condition prevails, the latch 1980 is allowed to move rearwardly under the influence of the spring 1986. Cam means are preferably utilized for accomplishing this controlling action, the cam means in the present instance being associated with a control cam shaft 1992 which forms a part of the control means for the sheet feed. The cam shaft 1992 is driven in timed relation to the control mechanism of

the machine, and is utilized to control the sheet stop fingers as 852 and the sheet feeding rollers at 1993. During the time when the platen MP is to be actuated independently of the platen MP-2 a rise on cam 1995, fixed on the cam shaft 1992, engages the rear face of a depending cam follower 1996 fixed on the rod 1983 to thereby hold the latch 1980 against engaging or rearward movement. At the time when the follower 1996 is about to ride off of the rise on the cam 1995, a rise on a cam 1997 engages the forwardly projecting foot portion of a bracket 1999 fixed to the cross bar 1985. The cam 1997 thereby acts to shift the platen MP-2 downwardly so that the cross bar 1968 thereof is located below the level of the shoulder 1981 of the latch 1980. Hence when the cam 1995 releases its restraining action upon the follower 1996, the spring 1986 shifts the latch 1980 rearwardly to engage the shoulder 1981 with the platen MP-2. The platen MP-2 is thus latched to the platen MP so that the actuation of the platen MP through its printing stroke by its normal actuating means is effective to produce a corresponding printing stroke of the platen MP-2.

Where a check such as the check S is being produced so as to require but a single impression V and a single impression A, the platen MP is operated through but two cycles of operation, in one of which the changeable data A are printed upon the check, and in the other of which the platen MP-2 is simultaneously operated to print the impressions V and N upon the check. It will be understood, of course, that in the event the check embodies a stub portion Sb as in the present case, so as to require duplicate impressions A, V and N, the platen MP is operated four times, in two of which the platen MP operates independently of the platen MP-2 to thereby print the changeable data A once upon the stub Sb and once upon the body of the check, and in the other two of the operations the platen mechanism MP operates the platen MP-2 to make an impression upon the stub Sb and the other impression upon the check. Upon completion of the desired printing stroke or strokes of the platen MP-2 the rise on the cam 1995 engages the cam follower 1996 to disengage the latch 1980 from the platen MP-2. Thus the changeable data and variable data derived from a single printing and control device D are printed on a check or sheet S, together with an identifying number N. Corresponding impressions are made in each line of the proof sheet by the platen PP, as will now be explained.

As best shown in Fig. 11, the platen sections 1785, 1786 and 1787 of the platen PP are not mounted in alignment since the printing impressions of variable data V and a number N made in any particular operation of the platen PP pertain to a printing device which follows the printing device which is then located at station V. As to any particular printing and control device D, the variable data V derived therefrom is printed on the proof sheet before the printing and control device reaches station V, and prior to the next operation of the platen PP the web W is advanced through a line spacing movement, and hence the platen section 1785 is so related to the platen sections 1786 and 1787 as to print the change data A in the same line as the previously printed impressions V and N. After the first operation of the platen PP, all of the platen sections 1785, 1786 and 1787 may be effective in a

printing stroke, but in each instance the changeable data A will be printed from one printing and control device in a particular line on the proof sheet, while variable and numbering data V and N pertaining to a succeeding printing and control device will be printed in the next line of the proof sheet. Therefore, the variable data V and changeable data A that are thus printed in any particular line of the proof sheet are related, which is to say, these data are derived from the same printing and control device.

In machines such as the one in which this invention is illustrated it is customary to pass an entire series of printing devices D through the machine even though printing impressions are to be made from only selected ones of such printing devices. The desired selection of printing devices is attained through the use of identifying means on the printing devices, such for example as the tabs TB or TBs, Fig. 4, and when a tab such as the tab TBs is detected upon a printing device, this printing device is passed through a machine without the formation of printing impressions therefrom. Thus with respect to such a printing device the platen mechanism MP remains in its upper or inactive position when the printing device is at station III. It will be evident of course that with respect to such printing device, the operation of the platen mechanism PP must also be altered, but since numerical data V must in some instances be printed upon the proof sheet in cycles of machine operation when the platen mechanism MP is thus inactive, a delay mechanism, which includes a Bowden cable 1996, Fig. 13, connected to the platen MP is utilized in control operation of the platen PP. Details of this operation and structure may be found in my copending application Serial No. 416,749, filed October 27, 1941, but it may be observed that such delay mechanism is operative to cause energization of the solenoid 1820 to thereby render the platen face 1785 ineffective to produce an impression from such a printing device when the printing device reaches station III.

The selective operation of the platen sections of the platen mechanism PP as above described is attained through selective operation of the solenoids 1820 and 1840, and such selective operation of the platen mechanism is also utilized in the printing of the page total PTT, the ledger total LT and the grand total GT. Thus it will be evident that during the printing of any one of such totals upon a proof sheet, there is a printing device D located at the printing station V, this being true because the printing device advancing means are inoperative during the total-taking operation of the machine. Hence in a total-taking operation the solenoid 1820 is energized so as to cause the platen section 1785 to assume its retracted position, and this prevents printing of an impression from the printing device at station V. It will also be observed that the numbering mechanism 1781 is intended to count the number of checks which have been printed by the machine, and hence it is usually desirable to avoid printing of a number opposite any one of the different types of totals. Therefore, during a total printing operation, the platen section 1787 is allowed to remain in its retracted position and to accomplish this the circuit to the solenoid 1840 is allowed to remain open during a total-printing operation.

From the foregoing description it will be apparent that the present invention enables the various data to be expeditiously printed not only

upon the checks or original sheets but also upon proof sheets. The platen mechanism of this invention is such that delayed operation of certain of the platen sections may be readily obtained, thereby to enable related data to be printed in the same line of a proof sheet through printing operations which are performed in different cycles of operation of the machine.

Hence, while I have illustrated and described the preferred embodiments of my invention, it is to be understood that these are capable of variation and modification and I therefore do not wish to be limited to the precise details set forth, but desire to avail myself of such changes and alterations as fall within the purview of the following claims.

I claim:

1. In a printing machine of the character described having a printing station, a variable printer having settable type elements located at said printing station, a numbering machine located at said printing station, and platen mechanism adapted for printing cooperation with set type elements of said variable printer and with said numbering mechanism, said platen mechanism including a shiftable supporting frame, a first platen section carried on said supporting frame in fixed relation thereto and adapted in a printing stroke to move into printing cooperation with set-up type elements of the type segments of said variable printer, and a second platen section mounted on said supporting frame for shiftable movement relative to said supporting frame whereby said second platen section may be shifted between active and inactive positions on said supporting frame, a stationary support adjacent to said platen, spring means acting between said stationary support and said second platen section and operable normally to retain said second platen section in its inactive relation when said supporting frame moves through a printing stroke, and means carried on said supporting frame for latching said second platen section in its active relation on said supporting frame when a printing impression is to be made by said second platen section from said numbering mechanism.

2. In a printing machine having a printing station and platen mechanism adapted to cooperate with printing means located at said printing station, said platen means comprising a supporting frame shiftable through a predetermined printing stroke, a platen member shiftably supported on said supporting frame for retracting movement from an active position on said frame to an inactive position, a stationary support adjacent to said platen, spring means urging said platen member toward said inactive position, cam means adapted to operate against the force of said springs to shift said platen member to its active position, an operating arm connected to said cam means, a stationary abutment mounted on said support adjacent said platen supporting frame and adapted to be engaged by said actuating arm as said platen member is shifted through its return stroke to thereby actuate said cam means to shift said platen member to its active position, a normally inactive stop member mounted on said stationary support and adapted to be shifted into the path of said actuating arm to operate said actuating arm in the other direction during a printing stroke of said platen to thereby render said platen inactive, and means mounted on said support for actuating said shiftable stop member into an operative position.

3. In a printing machine of the character described having a printing station, an anvil associated with said station, a variable printer and a numbering machine also located at said printing station, platen means for cooperation with said numbering machine, said variable printer and a printing device located on said anvil, said platen means comprising a supporting frame adapted for movement through printing and return strokes, a first platen section mounted on said supporting frame in stationary relation thereon and adapted in a printing stroke to cooperate with said variable printer, a second platen member mounted on said supporting frame for cooperation with said numbering mechanism and adapted for movement relative to said supporting frame to render said second platen section ineffective in a printing stroke of said supporting frame, a third platen section mounted on said supporting frame for cooperation with a printing device located on said anvil, said third platen section being shiftable from an effective position to an ineffective position relative to said supporting frame, means rendering one of said shiftable platen sections normally ineffective, means rendering other of said shiftable platen sections normally effective, and means operable on said shiftable platen sections to control the effectiveness thereof.

4. In a printing machine of the character described having a printing station, a pair of independent platens mounted at said printing station for independent movement along similar paths through printing and return strokes, means acting on said platens to yieldably urge the same through their return strokes and to their retracted positions, means for actuating one of said platens, through its printing stroke, and latch means operable to latch the two platens together for simultaneous actuation through their printing strokes by said actuating means.

5. In a printing machine having a printing station, platen mechanism at said printing station comprising a pair of platen members independently mounted for movement along similar paths through printing and return strokes, a platen actuating means, and means to render said platen actuating means operable selectively to actuate one or both of said platen members.

6. In a printing machine having a printing station, a pair of platens located at said printing station and separately mounted for independent movement through printing and return strokes, means for actuating one of said platens through a printing stroke, means for latching the two platens together whereby said one platen may be actuated independently of the other platen or both of said platens may be actuated in unison, sheet feeding means for feeding sheets to said printing station and including a control cam shaft, and cam means on said cam shaft operable to control the latching and unlatching of said platens.

7. In a printing machine of the character described having a printing station, an anvil associated with said station, variable printing means located at said printing station, platen means for cooperation with said printing means a printing device located on said anvil, said platen means comprising a supporting frame adapted for movement through printing and return strokes, a first platen section mounted on said supporting frame in stationary relation thereon and adapted in a

printing stroke to cooperate with a portion of said variable printing means, a second platen member mounted on said supporting frame for cooperation with other portions of said variable printing means and adapted for movement relative to said supporting frame to render said second platen section ineffective in a printing stroke of said supporting frame, a third platen section mounted on said supporting frame for cooperation with a printing device located on said anvil, said third platen section being shiftable from an effective position to an ineffective position relative to said supporting frame, means rendering one of said shiftable platen sections normally ineffective, means rendering other of said shiftable platen sections normally effective, and means operable on said shiftable platen sections to control the effectiveness thereof.

8. In a printing machine having a printing station, a pair of platens located at said printing station and separately mounted for independent movement through printing and return strokes, means for actuating one of said platens through a printing stroke, means for latching the two platens together whereby said one platen may be actuated independently of the other platen or both of said platens may be actuated in unison, and means operable to control the latching and unlatching of said platens.

9. In a printing machine having a printing station and platen mechanism adapted to cooperate with printing means located at said printing station, said platen means comprising a supporting frame shiftable through a predetermined printing stroke, a platen member shiftably supported on said supporting frame for retracting movement from an active position on said frame to an inactive position, spring means urging said platen member toward one of said positions, cam means adapted to operate against the force of said springs to shift said platen member to its other position, an operating arm connected to said cam means, a stationary abutment mounted adjacent said platen supporting frame and adapted to be engaged by said actuating arm as said platen member is shifted through its stroke in one direction to thereby actuate said cam means to shift said platen member to its other position, a normally inactive stop member adapted to be shifted into the path of said actuating arm to operate said actuating arm in the other direction during a stroke of said platen in the other direction to thereby cause said platen inactive to assume said one position, and means for actuating said shiftable stop member into an operative position.
